UNITED STATES PATENT OFFICE

GERTRUDE E. THOMPSON, OF ELGIN, ILLINOIS, ASSIGNOR TO VAN SICKLEN CORPORATION, OF ELGIN, ILLINOIS, A CORPORATION OF DELAWARE

DESIGN FOR A RADIOCABINET

Application filed March 26, 1931. Serial No. 39,254. Term of patent 3½ years.

To all whom it may concern:

Be it known that I, GERTRUDE E. THOMPSON, a citizen of the United States, residing at Elgin, in the county of Kane and State of Illinois, have invented a new, original, and ornamental Design for a Radiocabinet, of which the following is a specification, reference being had to the accompanying drawing, forming part thereof.

The figure is a perspective view showing

the front, side, and top of the cabinet embodying the features of the novel design, the side not shown being identical to that shown in the drawing.

I claim:

An ornamental design for a radiocabinet substantially as shown and described.

In witness whereof, I hereunto subscribe my name, this 21st day of March, 1931.

GERTRUDE E. THOMPSON.
